UNITED STATES PATENT OFFICE

JESUS R. SILVA AND ANTONY KRAHMER, OF EL PASO, TEXAS

BRUSH CONSTRUCTION

Application filed February 28, 1931. Serial No. 519,181.

This invention relates to sanitary shaving brushes especially designed for barbers' use, and has for an object the provision of a brush handle and separate sets of bristles individually arranged in a sanitary container and impregnated with a suitable soap solution so that a separate set of bristles may be provided for each customer as well as separate soap.

Another object of the invention is the provision of a brush handle of novel construction, to which the bristles may be quickly attached, and from which they may be quickly removed, the bristles being of an inexpensive character so that a customer may be served with a minimum amount of expense.

With the above and other objects in view, the invention further includes the following novel features and details of construction to be hereinafter more fully described, illustrated in the accompanying drawing and pointed out in the appended claim.

In the drawing:

Figure 1 is a sectional view of a sanitary shaving brush constructed in accordance with the invention.

Figure 2 is an enlarged sectional view on the line 2—2 of Figure 1.

Figure 3 is a detailed view showing a set of bristles removed from the handle.

Figure 4 shows a set of bristles arranged in a sanitary transparent container.

Referring to the drawing in detail where-in like characters of reference denote corresponding parts, the brush which is shown in Figures 1 and 2 is provided with a metal handle which includes a barrel 10. This barrel is provided at one end with an opening 11, and its opposite end is closed by means of a cup shaped member 12, from which extends an internally threaded socket member 13. The cup shaped member 12 is slidable within the barrel 10 and its outward movement may be limited by any suitable means. In-

ward sliding movement of the cup shaped member 10 is yieldingly resisted by a spring 14, one end of which bears within the cup shaped member while the opposite end bears against the inner end of the barrel.

Removably or threadedly secured within the socket member 13 is one end of a shank 15 whose opposite end carries a hook 16 and is disposed within the socket 17 provided with handle extension 18, the latter forming the brush head and receiving the bristles 19.

The brush is made up of relatively long bristles which are bent intermediate their ends and the bight portion thereby provided is wrapped or reinforced as at 20. This provides for convenient engagement within the hook 16, whereby the bristles are removably secured in place.

By pressing inwardly upon the cup shaped member 12, the hook 16 will be projected outwardly so that the bristles 19 may be readily removed and another set or bunch of bristles substituted.

It is preferred to supply these bristles in individual transparent sanitary containers 21, as shown in Figure 4 of the drawing and to impregnate these bristles with a soap solution as indicated at 22. Thus each customer may be provided with an individual set of bristles and individual soap.

The invention is susceptible of various other minor changes and the right is herein reserved to make such changes as properly fall within the scope of the claim.

What is claimed is:

A shaving brush comprising a handle including a hollow barrel of equal diameter throughout its length, having a closed inner end provided with an opening, a cap fitting within the opposite end of the barrel and serving as a closure therefor and provided on the inner surface thereof with an internally threaded socket, a rod extending through the opening of the closed end of the barrel and threadedly engaging with the socket member

of the cap, a spring surrounding said rod and abutting at one end with the closed end wall of the handle and at its opposite end with the interior of said cap for permitting movement of the cap under spring tension in a direction toward the closed end wall thereof, a frusto-conical shaped socket abutting with the closed end wall of the barrel, said rod being provided with a hooked extremity disclosed within said socket, bristles extending in the socket and detachably engaging with said hook.

In testimony whereof we affix our signatures.

JESUS R. SILVA.
ANTONY KRAHMER.
